UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

FUSE-PLUG.

1,328,782.

Specification of Letters Patent. Patented Jan. 20, 1920.

Application filed August 25, 1915. Serial No. 47,845.

To all whom it may concern:

Be it known that I, REUBEN B. BENJAMIN, a citizen of the United States, residing at Chicago, in the county of Cook and State 5 of Illinois, have invented new and useful Improvements in Fuse-Plugs, of which the following is a full, clear, concise, and exact description, reference being had to the accompanying drawing forming a part of this 10 specification.

My invention relates to fuse plugs, and more specifically to magazine fuse plugs, that is, to plugs in which a plurality of fuses are provided any one of which can be placed 15 in circuit with the plug contacts.

Among the objects of my invention is to provide a fuse plug which will be simple in construction, efficient in use and in which improved means are provided whereby the 20 different fuses can be placed in circuit, and which is easily operated to place the different fuses in circuit.

Further objects will appear from the description to follow taken in connection with 25 the appended claims.

In the drawings, in which I have illustrated two embodiments of my invention—

Figure 1 is an axial section of a magazine fuse plug embodying my invention; 30 Fig. 2 is a transverse section on the line 2—2 of Fig. 1;

Fig. 3 is a transverse section on the line 3—3 of Fig. 1;

Fig. 4 is a plan view of the connecting 35 device or switch plug used to connect the fuses with the plug contacts;

Fig. 5 is an axial section of a modification in which the switch plug is rotatably mounted;

Fig. 6 is a bottom view of the fuse carrying portion of the plug of Fig. 5; and

Fig. 7 is a plan view of the switch plug shown in Fig. 5.

Referring now to the drawing in detail and first to Figs. 1, 2, 3 and 4, the plug illustrated comprises an insulating contact and fuse supporting device, indicated in general at 10 a threaded shell contact 11, and a center contact 12 for engagement with the corresponding contacts of a receptacle, a plurality of fuses 13, and a connector device or switch plug 14 which can be inserted in various positions to connect the different fuses with the center and shell contacts 12 55 and 11. The supporting device 10 comprises

an insulating base 15 to which is secured a retaining cap or disk 16 by means of the center contact 12 and a plate 17 for clamping the fuses 13 in engagement with the shell contact 11. The base 15 is provided 60 with a plurality of longitudinally extending parallel passages 18 through which the fuses 13 extend, and is recessed as shown at 19 to provide a space for the connection from the fuses to the switch plug. The 65 base 15 is reduced, as shown at 20, where it is surrounded by the shell contact 11, and is provided with a plurality of grooves 21 extending between the passages 18 to accommodate a correspondingly grooved portion 70 of the shell contact 11 in which parts of the fuses 13 are located. The base 15 and shell 75 contact 11 are provided with corresponding grooves, as shown at 22, to permit the escape of the gases generated by the blowing of the fuses. The base 15 is also provided with a plurality of grooves 23 to provide an additional passage for the escape of the gases. The base 15 has an enlarged portion 24 forming a thumb piece by means of which 80 the plug may be screwed into the receptacle, and also forming a support for the retaining member which holds the insulating mica disk in place. The shell contact 11 has the usual screw threaded portion 25 and an inwardly extending flange portion 26 which is provided with grooves 27 and 28 corresponding to the grooves 21 and 22 of the base 15.

The plate 17 is provided with a plurality 90 of grooves 29 opposite the grooves 37 of the flange 26 between which grooves portions of the fuses are located. The center contact 12 comprises a hollow rivet or eyelet which extends through openings in the cap 16 and base 15, and is flanged over as shown at 30 and 31 to hold these parts together and to hold the fuses 13 securely in place between the plate 17 and flange portion 26 to insure a good contact. The fuses 13 are made in 95 pairs, each pair comprising a U-shaped portion 32 which is clamped or held between the plate 17 and flange 26, the arms of the U-shaped portions 32 extending into the passages 18, portions 33 located in the recesses 19 and extending radially outward, and portions 34 also located in the recesses 19 and extending at an angle to the portions 33. Conductors 35 are provided to afford a connection between the fuses and the switch 110

plug 14. These conductors 35 are wrapped around the portions 34 of the fuses as shown at 36 and are provided with parallel contiguous portions 37 which extend inwardly, 5 and upwardly bent portions 38 forming contacts for engagement with the contact of the switch plug.

The recesses 19 are closed by means of an insulating plate 39 of mica or other suitable 10 transparent or translucent material which extends beneath the conductors 35 and is held in place on the base 15 by means of a retaining member 40 which is flanged over the enlarged portion 24 of the base, as 15 shown at 41 and 42. The base 15 is centrally recessed as shown at 43 to receive the switch plug. This recess 43 is provided with a plurality of parallel grooves 44 which operate with corresponding ribs on the 20 switch plug to prevent relative rotation between the switch plug and base, when the switch plug is inserted. The switch plug 14 comprises a contact and conductor member 45 for engagement with the center contact 12, a 25 contact and conductor member 46 for connecting the member 45 with the contact portion 38, and a handle and supporting member 47 by means of which the plug is handled and which supports the members 45 and 46. The 30 contact member 45 comprises two spaced tongues 48 which extend within the center contact 12 when the switch plug is in position, and an eye portion 49 which is embedded in the insulating handle 47. This contact member 45 may be conveniently formed 35 from an ordinary spring split pin. The member 46 comprises a spring contact portion 50 for engagement with the contact portion 38, and a base portion 51 which lies between the spaced tongues 48 and is securely 40 held in place by forming a depression in the base 51, and a corresponding projection in one of the tongues 48 as shown at 52. An opening 53 is provided within the member 45 through which one of the tongues 48 extends. The member 47 comprises a portion 45 extending into the recess 43 of the base 15, a handle or thumb engaging portion 55 and an indicator 56 for determining when one 50 of the fuses is connected in circuit. The portion 54 is provided with a plurality of ribs 57 for engagement with the grooves 44 for preventing relative rotation between the switch plug and base when the former is inserted. The plug 14 is recessed as shown at 58 to receive the lower end of the spring contact portion 50 to hold it in place. The circuit through the plug is from the center contact 12, through the members 45, 46, 35 and 60 fuse 13 to the shell contact 11.

The use and operation of the plug is as follows: The contact and fuse supporting device 10 is screwed into a receptacle and the switch plug 14 is inserted to connect one 65 of the fuses 13 with the contacts 11 and 12.

If one of the fuses is blown the switch plug 14 is withdrawn and when it is desired to connect another fuse in the circuit the plug 14 is again inserted to connect another one of the fuses. By means of the transparent 70 insulating plate 39 it can be determined, by inspection, which of the fuses has been blown, and by means of the indicator 56 it can be determined which one of the fuses 75 will be connected when the switch plug is inserted. The manner in which the connection is made between the center contact 12 and the tongues 48 insures a quick break of the circuit between these parts and prevents arcing. The grooves 22, 23 and 29 80 permit the gases resulting from the blowing of the fuses to escape at the inner end of the plug. The non-rotatable connection between the switch plug 14 and base 15 prevents any possibility of turning the switch plug 14 85 when it is inserted which might result in arcing or making a poor contact.

In the modification of Figs. 5, 6 and 7 the parts 11, 12, 13, 16, 35, 39 and 40 are substantially the same as the corresponding 90 parts of the plug shown in Figs. 1, 2, 3 and 4 and will not be described in detail.

The insulating contact and fuse supporting device 59 of this modification is also substantially the same except that one side 95 of the hub 60 is made sloping as shown at 61 to permit the spring contact to ride up along this surface out of contact with the conductors 35. The switch plug 62 of this modification comprises a contact and conductor member 63 which may take the form of a split pin, a thumb piece 64 in which the member 63 is embedded, and a contact and conductor member 65 electrically connected with the member 63 and having a portion 100 movable into engagement with the conductor members 35. The member 65 comprises a base portion 66 which is held in place between the members of the split pin and a contact portion 67 which is movable into 105 engagement with the various conductor members 35 as the switch plug 62 is rotated. The thumb piece 64 is provided with a recess 68 into which the lower end of the member 65 extends to prevent the lower edge of 110 this member from catching on other portions of the plug as it is withdrawn. The thumb piece 64 is also provided with an indicator 69 for showing which one of the fuses is placed in circuit. The supporting 115 device 59 of this modification is shown recessed at 70 to provide an additional passage for the escape of the gases due to the blowing of the fuses. This passage will permit some of the gases to escape into the 120 central chamber of the support 59.

The use and operation of the plug of this modification is as follows: The shell contact 11 is screwed into a receptacle until the center contact 12 makes suitable contact with 130

the center contact of the receptacle. The switch plug 62 is then inserted in a position in which the contact portion 67 will engage one of the conductors 35. If the fuse which is thus placed in circuit is blown a new fuse may be placed in circuit when desired by simply rotating the switch plug to cause the contact portion 67 to ride up the sloping shoulder 61 and snap down into contact with 10 the succeeding conductor 35. Also if desired instead of rotating the plug without removing it to make the new connection the plug may be withdrawn and reinserted in a new position to make connection with a new 15 fuse.

Having thus described my invention what I claim as new and desire to secure by Letters Patent is:—

1. A fuse plug comprising an insulating base, contacts supported thereby for engagement with the contacts of a receptacle, a plurality of fuses also supported thereby, and means for selectively placing said fuses in circuit with said contacts comprising a 25 connector plug constructed to be inserted and withdrawn without removing the fuses from the receptacle, said connector plug being completely, readily and quickly detachable with respect to said insulating base by 30 a pull on the plug.

2. A magazine fuse plug comprising an insulating base, a shell contact supported thereby having an inwardly extending flange and a U-shaped fuse member having 35 the portion which connects its arms engaging said flange.

3. A magazine fuse plug comprising an insulating base, a shell contact supported thereby having an inwardly extending flange and a U-shaped fuse member having 40 the portion which connects its arms engaging said flange, said flange having openings through which said arms extend.

4. A magazine fuse plug comprising an insulating base, a shell contact supported thereby having an inwardly extending flange and a U-shaped fuse member having 45 the portion which connects its arms engaging said flange, said flange having openings through which said arms extend, and means for holding said portion against said flange.

5. A magazine fuse plug comprising an insulating base, a shell contact supported thereby having an inwardly extending flange and a U-shaped fuse member having 55 the portion which connects its arms engaging said flange, said base having an opening into which the arms of the fuse member extend.

6. A fuse plug comprising an insulating base, contacts supported thereby for engagement with the contacts of a receptacle, a plurality of fuses also supported thereby, and means for selectively placing said fuses 65 in circuit with said contacts comprising a

connector plug constructed to be inserted and withdrawn without removing the fuses from the receptacle, said connector plug and base being provided with interengaging means for preventing relative rotation when 70 the connector plug is inserted, said connector plug being completely, readily and quickly detachable with respect to said insulating base by a pull on the plug.

7. A fuse plug comprising an insulating 75 base, contacts supported thereby for engagement with the contacts of a receptacle, a plurality of fuses also supported thereby, and means for selectively placing said fuses in circuit with said contacts comprising a connector plug constructed to be inserted and withdrawn without removing the fuses from the receptacle, said connector plug and base being provided with tongue and groove interengaging means for preventing relative 85 rotation when the connector plug is inserted.

8. A fuse plug comprising an insulating base, contacts supported thereby for engagement with the contacts of a receptacle, a plurality of fuses also supported thereby, 90 and means for selectively placing said fuses in circuit with said contacts comprising a connector plug, said connector plug comprising a split pin and a contact member having a base portion between the split portions of the pin. 95

9. A fuse plug comprising an insulating base, contacts supported thereby for engagement with the contacts of a receptacle, a plurality of fuses also supported thereby, 100 and means for selectively placing said fuses in circuit with said contacts, said fuses having portions located adjacent the exposed end of the plug, and conductors leading from said portions, each conductor comprising 105 a member of sheet material having a portion embracing said fuse portion.

10. A fuse plug comprising an insulating base, a shell contact supported thereby having an inwardly extending flange adjacent 110 the entering end of the plug, a fuse having a portion engaging said flange, and means for holding said portion against said flange, said holding means including a member which constitutes a center contact. 115

11. A fuse plug comprising an insulating base, contacts supported thereby for engagement with the contacts of a receptacle, a plurality of fuses also supported thereby, 120 and means for selectively placing said fuses in circuit with said contacts comprising a member exposed to be accessible for manual operation, said connector plug being completely, readily and quickly detachable with respect to said insulating base by a pull on 125 the plug.

12. A fuse plug comprising an insulating base, contacts supported thereby for engagement with the contacts of a receptacle, a fuse also supported thereby, and means for 130

placing said fuse in circuit with said contacts comprising a connector plug constructed to be inserted and withdrawn without removing the fuse from the receptacle, said connector plug being completely, readily and quickly detachable with respect to said insulating base by a pull on the plug.

13. A fuse plug comprising an insulating base, shell and center contacts supported thereby, a plurality of fuses electrically connected to said shell contacts adjacent the entering end of the plug, and means for selectively placing said fuses in electrical connection with said center contact, said connector plug being completely, readily and quickly detachable with respect to said insulating base by a pull on the plug.

14. A fuse plug comprising an insulating base, shell and center contacts supported thereby, a plurality of fuses electrically connected to said shell contact adjacent the entering end of the plug, a plurality of contact members, one electrically connected with each fuse, supported by said base, and means for selectively placing said contact members in electrical connection with said center contact.

15. A fuse plug comprising an insulating base, shell and center contacts supported thereby, a plurality of fuses electrically connected to said shell contact adjacent the entering end of the plug, a plurality of contact members, one electrically connected with each fuse, supported by said base adjacent the outer end thereof, and means for selectively placing said contact members in electrical connection with said center contact.

16. A fuse plug comprising an insulating base, shell and center contacts supported thereby, for engagement with the contacts of the receptacle, a plurality of fuses also supported thereby, and means for selectively placing said fuses in circuit with said contacts comprising a connector plug, completely, quickly and readily detachable with respect to said insulating base by a pull on said connector plug without removing said base from said receptacle.

17. A fuse plug comprising an insulating base, shell and center contacts supported thereby, for engagement with the contacts of the receptacle, a plurality of fuses also supported thereby, and means for selectively placing said fuses in circuit with said contacts comprising a connector plug, completely, quickly and readily detachable with respect to said insulating-base by a pull on said connector plug without removing said base from said receptacle, said insulating base having an axial recess to receive said connector plug.

18. A fuse plug comprising an insulating base, shell and center contacts supported thereby, for engagement with the contacts of the receptacle, a plurality of fuses also supported thereby, and means for selectively placing said fuses in circuit with said contacts comprising a connector plug, completely, quickly and readily detachable with respect to said insulating-base by a pull on said connector plug without removing said base from said receptacle, said insulating base having an axial recess to receive said connector plug, said connector plug comprising an insulating handle portion.

19. A fuse plug comprising an insulating base, shell and center contacts supported thereby, for engagement with the contacts of the receptacle, a plurality of fuses also supported thereby, and means for selectively placing said fuses in circuit with said contacts comprising a connector plug, completely and quickly detachable with respect to said insulating base, without removing said base from said receptacle, said insulating base having an axial recess to receive said connector plug, said connector plug comprising an insulating handle portion, said handle portion having an extension forming an indicator member.

In witness whereof, I have hereunto subscribed my name in the presence of two witnesses.

REUBEN B. BENJAMIN.
